UNITED STATES PATENT OFFICE

CYRUS E. THOMPSON, OF WINFIELD, KANSAS

PAPER CLIP

Application filed April 11, 1932. Serial No. 604,525.

My invention relates to clips, and particularly to an improved paper clip or the like.

It is an important object of the invention to provide a clip which can be applied to papers, book pages, and other small objects at either end, and will securely retain the objects.

It is also an important object of my invention to provide a clip of this type which can be very cheaply manufactured from a single length of wire with few and inexpensive operations.

Other objects and advantages of the invention will be apparent from a reading of the following description and drawing, wherein for purposes of illustration I have shown a preferred embodiment of the invention.

In the drawing:

Figure 1 is a general side elevational view of the embodiment.

Figure 2 is a bottom plan view of Figure 1.

Most paper clips and the like must be engaged with the papers and the like at one end only, and this one end does not always securely hold the papers either because the cost of providing a sufficiently strong clip is prohibitive or the construction of the clip is such that it is difficult to apply and will not securely hold the objects to which it is applied. Usually, clips which are efficient are expensive and for that reason are not in demand where a low priced clip is sought. The device of the invention is so constructed that it may be made of fairly low cost material in a very simple manner, and yet be capable of being readily and quickly engaged with the papers or the like, and will then securely hold the papers or the like. This accomplishment will be better understood upon reference in detail to the drawing, wherein like numerals refer to like parts throughout the same. The numeral 5 generally designates the embodiment described.

A single length of wire of suitable gauge, is bent at its middle completely in a circle whereby the single convolution 6 is produced together with the return bends 7, 8 from which continue the straight leg 9 in a con-

verging manner in a vertical plane, one above the other as shown in Figure 1 substantially in the central vertical plane of the convolution 6. Where the end portions of the legs 9, 10 come together or converge their touching faces are provided with nicks or roughened cooperating surfaces as indicated at 11 for increasing the frictional grip of these portions of the legs. From the point 11 the extremity of the leg 9 is extended outwardly in a curved manner as indicated at 12, while the corresponding portion of the leg 10 is similarly oppositely extended and curved as indicated at 13, but the portion 13 of the leg 10 does not extend outwardly quite as far as does the extension 12 of the leg 9.

Reference to Figure 2 will disclose that the portion of the leg 10 extending beyond the point 13 is curved at 14 whereby to form a U-shape which terminates at 15 above the leg 9 whence the remaining portion of the leg 10 is transversely and angularly directed in a straight line as indicated at 16 and overlapped on the outward side of the leg 10 as indicated at 17.

A similar and opposite formation is given the corresponding part of the leg 9. However, the formation takes a slightly different shape in the case of the leg 9, since instead of being curved as is the leg 10 at 13 and 14, the leg 9 is not quite so curved, but has a squared portion 18 which extends beyond the end of the portion 14 as already indicated in previous description. The straight portion of the leg 9 is overlapped on the outside of the leg 9 at the point 19 just above the point indicated at 17 on the leg 10.

It will be observed that the return bends 7, 8 and the convolution 6 may be spread and papers or the like inserted therein whereby to be securely held. It is obvious that the portions 12, 13 at the other extremities of the legs are disposed so as to easily receive papers or the like inserted therewith, the papers being then held securely through the spring action of the legs and the roughened surfaces 11. The recited construction makes it possible to suspend articles in various manners, utilizing one or the other end of the clip or both ends thereof engaged with the support.

and the object being suspended. It will be observed that a busy man's time is considerably saved as well as his patience, since he can readily clip together papers by inserting them at the end of the clip, making it unnecessary to adapt any special technique in engaging the clip, or using both hands for this operation. Due to the mechanical relationship of the different parts of the device of the invention and the character of the parts the spring action of the device is very strong and lasting even when material of comparative low cost is utilized in its manufacture.

Though I have shown and described herein a preferred embodiment of the invention, it is to be definitely understood that I do not desire to limit the application of the invention thereto, and any change or changes may be made in materials, and in structure and arrangement of parts, within the spirit of the invention and the scope of the subjoined claims.

What is claimed is:—

1. A clip made of one piece of wire having a coil with its axis across the clip, two resilient clamping lever arms composed of one strand of wire, said arms leading from opposite ends of the coil to engagement with each other, the free end portion of each of said arms being oppositely return bent and the end of the strand brought over and against the outside of the arms to form springedly engaged loops.

2. A clip made of one piece of wire having a coil with its axis across the clip, two resilient clamping lever arms composed of one strand of wire, said arms leading from opposite ends of the coil to engagement with each other, the free end portion of each of said arms being oppositely return bent and the end of the strand brought over and against the outside of the arms to form springedly engaged loops, said loops being slightly oppositely deflected at their outward ends so as to facilitate insertion of papers and the like therebetween.

3. A clip made of one piece of wire having a coil with its axis across the clip, two resilient clamping lever arms composed of one strand of wire, said arms leading from opposite ends of the coil to engagement with each other, the free end portion of each of said arms being oppositely return bent and the end of the strand brought over and against the outside of the arms to form springedly engaged loops, said loops being slightly oppositely deflected at their outward ends so as to facilitate insertion of papers and the like therebetween, one of said loops being longer than the other for further facilitating insertion and attachment to papers and the like.

4. A clip made of a single piece of wire having a coil with its axis across the clip, a resilient clamping-lever arm proceeding

from each end of the coil into spring engagement with each other, said arms being substantially straight, oppositely formed hairpin bends on the outer end portion of the arms, the ends of the wire forming the bends having a portion directed over and against the outside of the associated arm, the bent portion only of the legs being superposed and engaged.

5. A clip made of one piece of wire having a coil with its axis across the clip, two resilient clamping lever arms composed of one strand of wire, said arms leading from opposite ends of the coil to engagement with each other, the free end portion of each of said arms being oppositely return bent and the end of the strand brought over and against the outside of the arms to form springedly engaged loops, roughened gripping surfaces on the loops where they touch.

In testimony whereof I affix my signature.

CYRUS E. THOMPSON.
